H. L. KENNEDY,
TRAVELER'S BAG OR GRIP.
APPLICATION FILED JUNE 8, 1914.

1,143,711.

Patented June 22, 1915.

UNITED STATES PATENT OFFICE.

HOWARD L. KENNEDY, OF FORT WAYNE, INDIANA.

TRAVELER'S BAG OR GRIP.

1,143,711.

Specification of Letters Patent.

Patented June 22, 1915.

Application filed June 8, 1914. Serial No. 843,675.

To all whom it may concern:

Be it known that I, HOWARD L. KENNEDY, a citizen of the United States, residing at Fort Wayne, in the county of Allen 5 and State of Indiana, have invented new and useful Improvements in Travelers' Bags or Grips, of which the following is a full, clear, and exact description.

My invention relates to a traveler's bag 10 or grip, and particularly to one made entirely of metal.

The object of my invention is to provide a sheet metal traveler's bag or grip which will be comparatively light and strong, and 15 which is rain-proof and dry. This I accomplish by the means hereinafter fully described and as particularly set forth in the claims.

In the drawings: Figure 1 is a perspective 20 view of a sheet metal grip embodying my invention. Fig. 2 is a vertical transverse section through the same. Figs. 3 and 4 are perspective views of a fragment of said grip showing the construction of the upper 25 corners of the same. Fig. 5 is a sectional view of a detail of said grip.

The body of my improved grip is rectangular in shape and the longer sides A and bottom B are made in one piece, and 30 the bottom thereof is corrugated longitudinally.

The ends C of the body have their lower and vertical edges inclosed by and suitably seamed to the end edges of the longitudinal 35 sides and bottom thereof. Above the horizontal plane of the upper edge of the vertical surface of the side the edges of the ends C incline upward at corresponding angles and the vertex thereof is truncated, and 40 these upper edges e are reinforced by rolling them inward around a wire d, substantially as shown in the drawings. The ends C, and, if desired, the longitudinal sides of the body also, may be paneled; the former, prefer- 45 ably, by a rectangular panel below the plane of the top of the longitudinal sides, and a triangular shaped panel above the same, and the latter (the longitudinal sides) by a rectangular panel, substantially as shown 50 in dotted lines in Fig. 1 of the drawings. Any or all of these panels may be omitted, although I much prefer their use as they greatly strengthen the sides of the body and improve the appearance of the grip.

55 The upper portions of the longitudinal sides of the body of the grip extend beyond

the vertical surface thereof and incline upward between and at the same pitch as the upper edges of the ends C of said body to form sheds a. The sheet metal forming 60 these sheds is bent inward and doubled upon itself, and the edge of this inwardly bent metal terminates at the inner angle of the vertical portions of said sides and the sheds and surrounds a longitudinal wire b that 65 extends from end to end of the body and greatly strengthens and reinforces the upper edges of the sides thereof. The ends of the doubled sheet metal of the sheds a is split along the line of the bend thereof to 70 form lips e and f, and one of these lips, e, laps against the adjacent inner vertical surface of the end C and the other, f, extends over the upper edge of the same and then is bent downward and lapped against the 75 outer surface of the said end opposite lip e, and is riveted to said end and lip e by a suitable rivet e' in such manner as to make a very strong and yet simple corner for the body.

The top of my improved grip is closed by two lids or covers E and F that correspond to the sides of the roof of the house to the shape of which said grip was hereinbefore compared. The lids are hinged to the angle between the longitudinal sides of the body and the sheds by means of several hinge-plates G that are riveted to the inner surfaces of the vertical portions of the sides and extend up through slots in said angles 90 and have their upper edges formed into knuckles H. The lower edges of the covers E are likewise provided with a series of knuckles j that are in staggered relation to knuckles H and are connected thereto by 95 means of a suitable wire pintle k the ends of which latter are covered and confined by the downwardly flanged end edges m of the covers that lap over the upper inclined edges of the ends of the body.

In order to prevent lateral vibration or displacement of the peaked upper portion of the end-walls C when the grip is closed, I provide the underside of cover F with a transverse metal fin n, n, near each end 105 thereof between which and the end edges m the upper inclined edges of the end-walls enter.

The upper edge of one of the covers, E, terminates below the ridge of the top of 110 the body and is strengthened by being rolled back upon itself, and it is provided with

suitable sockets K, K, for the counterpart guide-bolts K', K', affixed to the other cover, and is also provided with a lock J for the reception of the bolt-counterpart I, attached 5 to the other cover, as shown. I make no claim to the construction and arrangement of the guide-bolts and sockets; they may be of any suitable design. The other cover F extends up over the ridge of the top of the 10 grip and down the opposite incline thereof sufficiently for its upper edge (which is strengthened by being lapped back upon itself) to lap over the upper edge of the cover E. The guide-bolts K' and the bolt 15 counterpart of the lock are secured to this overlapping edge of cover F, and at the center of length of the flattened ridge of said cover, it is provided with a suitable handle.

What I claim as new is:

- 20 1. A sheet metal traveler's grip or bag having a body comprising rectangular vertical longitudinal sides and ends that have their upper edges inclined upward from the top of the longitudinal sides toward each other, and inclined covers for said body; the upper portion of each of said longitudinal sides extending upward in an inclined direction under the lower edge portion of one of said covers and doubled back under it 25 self and terminating in a wire selvaged edge, and having its end edges above the sides split and embracing the adjacent portions of the upper edges of the ends, and one of said covers having its upper edge extend beyond the ridge of the grip and down the opposite incline and overlapping the top edge 30 of the other cover.
- 35 2. A sheet metal traveler's grip or bag

Copies of this patent may be obtained for five cents each, by addressing the "Commissioner of Patents, Washington, D. C."

having a body comprising rectangular vertical longitudinal sides and ends that have 40 their upper edges inclined upward from the top of the longitudinal sides toward each other, and inclined covers for said body; the upper portions of said longitudinal sides extending upward in an inclined direction 45 under the lower edge portion of said covers and one of said covers having its upper edge extend beyond the ridge of the grip and down the opposite incline and overlapping the top edge 50 of the other cover, and having transverse fins depending from its under surface between which and the downwardly flanged edges of said cover the adjacent upper edges of said end-walls are adapted to be confined.

3. A sheet metal traveler's grip or bag having a body comprising longitudinal sides and bottom made in one piece of metal and said bottom corrugated, and end walls having 60 panels; and having the upper edges thereof above the plane of said longitudinal sides inclined upward toward each other; one of said covers having its upper edge extend beyond the ridge of the grip and down the 65 opposite incline of the other cover, and having transverse fins depending from its under surface between which and the downwardly flanged edges of said cover the adjacent upper edges of said end-walls are adapted to be confined.

In witness whereof I have hereunto set my hand this 21st day of May, 1914.

HOWARD L. KENNEDY.
